UNITED STATES PATENT OFFICE.

ALBERT W. COX, OF CHICAGO, ILLINOIS, ASSIGNOR OF ONE-HALF TO DAVIS
M. LELAND, OF SAME PLACE.

RECEPTACLE FOR BURNING REFUSE.

SPECIFICATION forming part of Letters Patent No. 643,593, dated February 13, 1900.

Application filed February 25, 1899. Serial No. 706,834. (No model.)

To all whom it may concern:

Be it known that I, ALBERT W. COX, a citizen of the United States, residing at Chicago, in the county of Cook and State of Illinois, have invented certain new and useful Improvements in Receptacles for Burning Refuse, of which the following is a specification.

The invention relates to receptacles for burning refuse; and it consists in certain 10 tails of construction and arrangement of parts hereinafter described in the specification, illustrated in the drawings, and pointed out in the claims. Its object is to provide a portable device for safely confining and cremating 15 light trashy refuse, such as paper, leaves, shavings, and the like which accumulate about house-lawns, streets, offices, stores, and alleys, and which when burned in the open air is liable to be blown about and scattered 20 by the wind, thus endangering surrounding or adjacent property.

It consists in a corrugated iron body of suitable size, preferably cylindrical in form, provided with a bottom of suitable diameter to 25 fit within the inner projections of the corrugations and secured thereto by bolts or rivets, leaving openings between the bottom and walls of the cylinder within the corrugations; also, openings may be provided for the 30 admission of air in each corrugation and above the bottom near the base of the cylinder. These corrugations, in connection with the openings, afford draft-flues and prevent the walls from becoming unduly heated, as would 35 be the case in a plain surface. A surrounding jacket or covering incloses the cylinder, which jacket is secured by rivets to the outward projections or angles of the corrugations and is provided with feet or openings 40 at its base, whereby air may be admitted beneath the bottom or floor of the burner, the bottom being situated a suitable distance above the base of the jacket.

In the drawings which fully illustrate the 45 invention, Figure 1 is a perspective view of my device. Fig. 2 is a vertical section. Fig. 3 is a bottom plan view.

Referring more specifically to the drawings

by number, 1 is the interior corrugated cylinder, provided with the bottom 2. 50

3 is an outer closure or jacket surrounding the cylinder 1.

5 represents openings at or near the base of the exterior jacket for the admission of air beneath the bottom. 55

6 are handles by which the device may be conveniently moved.

The interior corrugations prevent the refuse to be burned from packing closely against the sides, and each affords an air channel or 60 flue for accelerating the combustion of the material to be consumed, also for the upward passage of air-currents between said cylinder and the surrounding jacket, and prevents undue heating and burning out of said 65 cylinder. I also may provide the fluted or corrugated walls of the cylinder 1 with a series of lateral draft or air openings 7, arranged in a plane above the bottom 2 and communicating with the fire-chamber to promote com- 70 bustion, and therefore increase the burning capacity of the device, and thus more readily and quickly dispose of the refuse.

Having thus fully described my invention, what I claim therein as new, and desire to secure by Letters Patent, is— 75

1. A portable refuse-burner consisting of a corrugated or fluted cylinder, having a bottom arranged therein at its base, said cylinder adapted to form a series of draft-passages at 80 the edge of said bottom and having an additional series of lateral draft-openings therein, arranged a suitable distance above said bottom, and a jacket or casing inclosing said cylinder or fire-pot and having a series of air-inlets 85 in its bottom edge, substantially as specified.

2. A portable refuse-burner, comprising a corrugated or fluted cylinder or fire-pot, and an imperforate bottom arranged therein, near the base, with its edges touching, or in contact with, the inner, or reentrant, angles of said fluted or corrugated cylinder, substantially as set forth. 90

3. A portable refuse-burner, comprising a corrugated or fluted cylinder or fire-pot, an 95 imperforate bottom arranged therein a short

distance above the base, said cylinder having a series of lateral draft-openings arranged a short distance above said bottom, and in communication with the combustion-chamber, substantially as set forth.

4. A portable refuse-burner, comprising a corrugated or fluted cylinder, an imperforate bottom arranged therein a short distance

above the base, and a jacket inclosing said cylinder, substantially as set forth. 10

In testimony whereof I affix my signature in presence of two witnesses.

ALBERT W. COX.
